(57) **CLAIM**

The ornamental design for pants, as shown and described.

DESCRIPTION

FIG. 1 is a front elevational view of pants showing our new design;

FIG. 2 is a rear elevational view thereof;

FIG. 3 is a front right perspective view thereof in a second position; and,

FIG. 4 is a rear left perspective view thereof in the second position.

The evenly spaced dashed lines represent unclaimed stitching. The vertical shading located within the panels at the bottom, medial side of each leg of the pants represents a ribbed material.

1 Claim, 4 Drawing Sheets
